UNITED STATES PATENT OFFICE

2,383,301

VERTICAL PIANO ACTION

Cyril Farny, St. Charles, Ill., assignor to The Rudolph Wurlitzer Company, Chicago, Ill., a corporation

Application March 10, 1944, Serial No. 525,862

8 Claims. (Cl. 84—253)

This invention relates to an action for a vertical piano, and more particularly in respect to the character of construction of the back check and the bridle strap wire.

It has heretofore been common practice to provide a vertical piano action with a back check wire having its lower end nested in a hole bored in the upper surface of the wippen, provided at its upper end with a wooden back check block having the usual felt cushion thereon.

In addition thereto it has been the practice to separately insert and secure in the upper surface of the wippen a bridle strap wire having a looped or curled end for anchoring the bridle strap. The assembly of these several pieces in each of the many units of the action has always been tedious and time consuming, reference being had in respect to such construction and the action in its entirety, to the Socin Letters Patent No. 2,239,204, issued April 22, 1941 for "Upright piano," and No. 2,324,037, issued July 13, 1943, for "Piano action."

It is the purpose of this invention to simplify and render more economical in production and assembly that portion of the piano action comprising the back check and the bridle strap wire. This may be accomplished by stamping from any suitable sheet material a strip of suitable length and width, splitting down one edge thereof and forming it to provide a one piece integral back check and bridle strap wire, and wherein the back check portion is of such width as to permit of forming a head thereon to receive a felt cushion, the bridle strap wire portion is sufficiently narrow to permit its free end to be curled as an anchor for the bridle strap, and the opposite end of said strip forming a common base for said portions which may have its surface knurled for insertion in the wippen.

By means of this construction not only are the three pieces heretofore employed reduced to a single piece, but the assembly thereof is much simplified. Wherein the material may be of metal or like material having bending characteristics, while formed of one piece or joined at their base, they may be bent, adjusted or regulated independently of each other. Thus the same advantages and functions are obtained wherein a one piece back check and bridle strap wire is provided by permanently joining them above their base before assembly, and wherein they have a common one piece base for mounting as a unit in the wippen.

The full nature of the invention will be understood from the accompanying drawing and the following description and claims:

Fig. 1 is a side elevation partly in section showing a portion of the piano action unit. Fig. 2 is a perspective view of the one piece back check and bridle strap wire illustrating in dotted lines its formation from a single strip. Fig. 3 is a perspective view of the head portion of the back check shown in Fig. 2, with the cushion felt mounted thereon.

In the drawing there is illustrated a portion of a piano action unit, including a wippen 10 having the usual cushion 11, for engagement by a lever, not shown. Said wippen is pivotally supported by a flange 12 from the action rail 13. Pivotally mounted upon the wippen by the flange 14 there is the usual jack 15 engageable with a hammer butt which carries a hammer 17. Said hammer butt is pivotally supported upon the action rail by the flange 18 and is provided with a rearwardly-extending hammer check 19.

The back check comprises the shank portion 20, the base portion 21 and the head portion 22. The bridle strap wire extends upwardly from the common base portion 21 having a shank portion 23 and a curled head 24 to which the bridle strap 25 is connected.

As indicated by dotted lines in Fig. 2, both the back strap and the bridle strap wire are stamped and formed from a strip of material, such as metal or the like, by slicing one end thereof to form the bridle strap of relatively narrow width. Such narrow strap terminates at its lower end in the common and integral base portion 21, having its upper end slightly laterally bent away from the remaining portion of the strap and with its free end curled to provide the head 24. The remaining portion of the strap, which is of relatively greater width, forms the shank 20 of the back check which terminates in the wide head portion 22 suitably curved or dished to provide a seat for the felt cushion indicated at 26.

The common base portion 21 may be roughened or knurled for frictional or clamping engagement in a suitable slot provided in the wippen, whereupon the shank portions 20 and 23 may be bent and adjusted as may be desired for the proper functioning of the action.

The above description of the structure as shown in the accompanying drawing is illustrative of one embodiment of the invention. However, both the back check shank and bridle strap wire, or either, may be formed of wire, or of any desired cross sectional shape, and of various materials integral with each other or permanently joined together to provide a unitary structure

having a common base for mounting in the wippen.

The invention claimed is:

1. In a piano action having a wippen, a one piece back check and bridle strap wire secured thereon to extend upwardly therefrom, said back check and bridle strap wire comprising a stamping from sheet material partially split to space their respective shank and head portions from each other and provide a common base portion, the head of said bridle strap wire being formed to receive a bridle strap and the head of the back check being of a width to provide a cushioning seat.
  2. In a piano action having a wippen, a back check and bridle strap wire secured thereon to extend upwardly therefrom, the shank portions thereof being flat to provide a flat base secured within said wippen and a correspondingly wide head portion on said back check for providing a cushioning seat, the free end of said bridle strap wire being formed to receive a bridle strap.
  3. In a piano action having a wippen, a back check and a bridle strap wire formed from a single strip of material, said bridle strap wire being of relatively less width than said strip with its free end formed to receive a bridle strap, said back check having a shank portion of relatively greater width than said wire with a head portion of substantially the width of said strip to provide a cushioning seat.
  4. In a piano action having a wippen, a one piece back check and bridle strap wire secured thereon to extend upwardly therefrom, the shank portions thereof being spaced from each other near their upper free ends, the upper free end of said back strap being of a width to provide a cushioning seat, the upper free end of said bridle strap wire being formed to receive a bridle strap, and said shank portions terminating at the lower end in a common base portion adapted to be secured in said wippen.
  5. In a piano action having a wippen, a back check and bridle strap wire secured thereon to extend upwardly therefrom, said back check and bridle strap wire being formed from a single piece of material split down one side thereof, one split portion of relatively narrow width provid-

- ing the bridle strap wire and the remaining portion being relatively wider to provide the back check, the free end of said bridle strap wire being formed to receive a bridle strap and the free end of said back check being the combined width of its shank portion and the bridle strap wire to provide a cushioning seat.
6. In a piano action having a wippen, a back check and bridle strap wire secured thereon to extend upwardly therefrom, said back check and bridle strap wire being formed from a single piece of sheet material split down one side thereof, one split portion of relatively narrow width providing the bridle strap wire and the remaining portion being relatively wider to provide the back check, the free end of said bridle strap wire being curled to provide a loop for a bridle strap and the free end of said back check being the combined width of its shank portion and the bridle strap wire to provide a seat for a cushion felt, and said back check and bridle strap wire having a common base portion with the bridle strap wire bent laterally from the shank portion of the back check.
7. In a piano action having a wippen, a unitary back check and bridle strap wire secured thereon to extend upwardly therefrom, the shank portions thereof being spaced from each other toward their upper free ends, a cushioning seat of greater width than the shank portion provided on the upper free end of the shank of the back check, and the shank portions of the back check and bridle strap wire terminating at their lower ends in a common base portion adapted to be secured in said wippen as a unitary structure.
8. In a piano action having a wippen, a unitary back check and bridle strap wire secured thereon to extend upwardly therefrom, the shank portions thereof being joined at their lower ends to provide a common base portion adapted to be secured in said wippen, the upper shank portions thereof being spaced from each other near their upper free ends, and a head portion provided on the upper free end of the back strap shank portion of a greater width to provide a cushioning seat.

CYRIL FARNY.
